(57) **CLAIM**

The ornamental design for a variable-angle reciprocating saw, as shown and described.

DESCRIPTION

FIG. 1 is an isometric view of the variable-angle reciprocating saw.

FIG. 2 is another isometric view of the variable-angle reciprocating saw of FIG. 1.

FIG. 3 is a right side view of the variable-angle reciprocating saw of FIG. 1.

FIG. 4 is a left side of the variable-angle reciprocating saw of FIG. 1.

FIG. 5 is a top view of the variable-angle reciprocating saw of FIG. 1.

FIG. 6 is a front view of the variable-angle reciprocating saw of FIG. 1; and,

FIG. 7 is a back view of the variable-angle reciprocating saw of FIG. 1.

A bottom view has not been shown because it is the mirror image of the top view. The environmental structure shown in dotted lines in FIGS. 1-7 is for illustrative purposes only and forms no part of the claimed design.
